LUDWIG WURZBURG, OF SAN FRANCISCO, CALIFORNIA.

DOUBLE-SEAMING AND VACUUMIZING MACHINE.

1,028,652.

Specification of Letters Patent. Patented June 4, 1912.

Application filed September 25, 1908. Serial No. 454,811.

To all whom it may concern:

Be it known that I, LUDWIG WURZBURG, a subject of the King of Great Britain, residing at San Francisco, in the county of San Francisco and State of California, have invented new and useful Improvements in Double-Seaming and Vacuumizing Machines, of which the following is a specification.

The objects of the present invention are, first, to provide a machine for double-seaming cans, either the bottom of a can to the body thereof to form the can, or the top to a filled can to close the can, which machine shall be simple and of great capacity in proportion to its size; second, to provide a machine of this character, which will not only effect the above operation of double-seaming the top to the can, but, while so doing, will also vacuumize the can, thus forming a perfect indication that the can has been hermetically sealed.

In the accompanying drawings, Figure 1 is a broken plan view of the machine; Fig. 2 is a vertical section diametral through the vacuumizing and seaming chambers; Fig. 3 is a detail perspective view of a can holder; Fig. 4 is a broken detail plan view of the same and a portion of the delivery valve; Fig. 5 is a vertical section through one of the pockets; Fig. 6 is a side view; Fig. 7 is an enlarged section of the feeding apparatus.

General arrangement.—1 indicates the casing of a double-seaming chamber 2, mounted on legs 3, 4 indicates a vacuumizing chamber, and 5 a discharge chamber. By means to be presently described, the cans 26 and tops 99 are fed into the vacuumizing chamber, and therein the air is exhausted from the can. The can with a top thereon is then delivered to the seaming chamber, where it is double-seamed, while a vacuum is maintained therein. From the seaming chamber it is transferred to the discharge chamber, by means of which it is discharged on to a suitable belt. Means are also provided for preventing the admission of air from the discharge chamber into the seaming chamber.

Feeding.—The cans are fed upon the upper portion of an endless traveling belt 6, and the tops are supplied upon the upper surface of the lower portion of an endless traveling belt 7, lying immediately over the endless belt 6. The belt 6 which carries the cans returns underneath, while the belt

7 which carries the top returns overhead. These belts arrive at the machine in a direction substantially tangential to the vacuumizing chamber, and the tops and cans are guided thereon by suitable side guides 8, 9. Mounted adjacent to the outer edges of said belts is a vertical rotating shaft 10 rotated by a gear wheel 92 meshing with a gear wheel 93 on a shaft 18 to be presently described, and upon said shaft 10 are secured upper and lower rotary transmitters 11, 12, each formed with three fingers 13, 14, respectively, adapted to respectively pass over the lower portion of the upper belt 7 and the upper portion of the lower belt 6 and thus to engage the tops and cans on said belts. Therefore, with each movement through one-third of a revolution of the transmitter shaft, a can and a top are displaced from the belts, and are moved through an opening 15 in the wall of the vacuumizing chamber, into one of a circular series of pockets 16 formed in a rotary valve 17 mounted upon a vertical shaft 18, rotated by means to be presently described. The gear wheel 92 has a diameter one-half of that of the gear wheel 93, and the valve 17 and the transmitters are so related that, at the time the fingers 13, 14 are actuated to shift a can and its top toward the valve, a pocket 16 in the valve has arrived at the proper position to receive such a can and top. The top so transferred falls from the belt 7 on to the top of the can in said pocket, as shown in Fig. 6.

Vacuumizing.—The valve 17 fits snugly within the casing of the vacuumizing chamber 4, and the bottom of each pocket is enlarged or undercut on the inner side, as shown at 98, to receive the projecting edge of the bottom of the can. The part which supports the can is in the form of a tooth, as shown at 25, spaced on each side from the remainder of the valve to permit of the entry thereinto of the arms of the can holder 23 hereinafter described. In the inner surface of the wall of the vacuumizing chamber is formed a circumferential groove 21 which is connected by a pipe 19 with an exhaust pump 20. Said groove extends circumferentially in said wall only between points each of which could not be connected by any one of the pockets either with the external atmosphere or with the double seaming chamber. The object of the groove is to continue the connection between the

exhaust pump and pocket for a considerable angular distance in the revolution of the latter, so as to thoroughly exhaust the pocket and the can contained therein. The 5 vertical shaft 18 is rotated by a gear wheel 94 meshing with a gear wheel 97 of equal diameter, carried by the lower hub-shaped portion 28 of a carrier hereinafter described, so that the valve rotates in unison with the 10 carrier. At the back of each pocket the valve is formed with a recess containing a coiled spring 22, which, when a pocket arrives at the opening in the valve casing, projects the can radially outward.

15 *Can carrier.*—When a can with the top thereon is projected by its spring into the double-seaming chamber it is pushed on to a semi-annular holder 23 on a vertically movable bar 54 carried by the main central portion 20 of a rotary carrier 24, which holder is of such form as to be able to mesh with the tooth-shaped projection 25 of the valve as said valve and the carrier rotate close to each other. The can holder is slightly 25 higher than the projection 25 and its arms have beveled ends to raise the can, so that it no longer rests upon the projection 25 but upon the can holder, and revolves therewith. Said carrier 24 has a tubular lower 30 portion 28 which passes through a bearing 27 formed in the bottom of the casing of the double-seaming chamber and has an annular shoulder 29 resting on said bearing. Through said tubular lower end 28 passes a 35 shaft 30 the upper end of which rotates in a bearing 31 formed on the cover of the double-seaming chamber, and the upper portion 32 of the carrier rotates around said bearing. Said upper and lower portions 32, 40 28, are preferably made detachable from the main portion, which comprises a cylindrical hub-shaped part 33, and a suitable number, as six of upper and lower radially extending arms 34, 35. Said arms form 45 bearings for upper and lower spindle shafts 36, 37. The upper shafts 36 carry heads 38 and are rigidly connected to pinions 39 which rotate in recesses in the upper arms 34, while the lower spindle shafts 37 can 50 slide vertically in their bearings in the lower arms 35, being formed with grooves 40 which are engaged by keys 41 on pinions 42 contained in recesses in said lower arms. Said upper and lower pinions 39, 42 are engaged 55 by gear wheels 43, 44, mounted upon the central shaft 30. Said central shaft and the carrier are driven by bevel gears 45, 46, which are driven by bevel pinions 47, 48, on a transverse shaft 49 driven from any 60 source of power. Each lower spindle shaft 37 carries a head 50 which is adapted to engage the bottom of the can, and said shaft is formed with a circumferential groove 51 which is engaged by a fork 52 secured to an 65 arm 53 extending outwardly from the lower

end of a vertical bar 54 which is formed with a T-shaped extension 55, the cross member 56 of which slides in a groove 57 formed upon the outside of the hub 33 of the carrier by securing plates 58 thereon (Fig. 4). This vertical bar 54 carries both the support 23 on to which the can is delivered, and also at its upper end a semi-annular guide 59 which guides and maintains the can top in position upon the top of the can when the can slides into position upon the support 23, and also assist in guiding the can when discharging it. The bar 54 also carries two forks or yokes 60 which engage the inner side of the can to arrest the can and center it when delivered on to the holder. They also assist in carrying away the can from the delivery valve.

Double seaming.—As the carrier rotates, each can thereby carried away from the vacuumizing chamber is raised by means of a cam rail 61 which engages the lower end of the spindle shaft 37, and by an incline thereon raises said shaft until the top of the can is engaged by the head 38 of the upper spindle shaft 36. Thereby the can is firmly clamped between the head 38 and the head 50, and, by the rotation imparted to the two spindle shafts, the can is correspondingly rotated. It is now, in the rotation of the carrier, brought to such position that the edge of the can top is engaged by a roughing roller 70. Said roughing roller 70 and also a finishing roller 71 are carried by horizontal slide plates 72, 73, which slide in a radial direction in a tool holder 74 formed upon the corresponding arm of the carrier. Each slide plate is normally pressed radially outward by a coiled spring 75 in a recess in the tool holder, and attached at one end to a pin 76 depending from the slide plate. The slide plates at their outer ends carry anti-friction rollers 77, 78, which are adapted to abut against cam rails 80, 79, lying in different horizontal planes, the roughing and finishing rollers themselves lying in the same horizontal plane. The roughing roller is first pressed inward by the cam rail 80, and then the finishing roller is pressed inward by the cam rail 79. During the time that the can is being seamed, vacuum is maintained in the seaming chamber by means of a pipe 81 leading to a second vacuum pump 82 operated independently of the first pump. By this arrangement there is avoided any variation of the pressure in the seaming chamber which would otherwise be caused by the successive introduction of fresh cans thereinto, as the cans before being introduced into the seaming chamber have been sufficiently exhausted of air in the vacuumizing chamber.

Discharge.—After the finishing roller leaves the second cam rail, and the top has

thus been double seamed upon the can, the can is engaged by an oblique or intersecting stationary cam rail 84, which causes said can to enter one of three pockets 85 in a rotary discharge valve 86 in a discharge chamber 5. Said valve is driven by a gear wheel 95 on its shaft which meshes with an intermediate gear wheel 96 which in turn meshes with the gear wheel 94. The wheels 95 and 96 being of half the diameter of the gear wheel 94, the valve 86 is rotated at twice the angular velocity of the carrier and of the valve in the vacuumizing chamber. By this valve 86 the can is carried to a position over a belt 87 at which point the casing of the chamber 5 is open, as shown, at 88, to permit the can to be discharged radially outward, which is immediately done by means of a spring 89 at the back of the pocket in the discharge valve. In order that no free air may be carried into the seaming chamber by the discharge valve in its rotation, each pocket, after discharging the can on to the discharging belt, is exhausted of free air by means of a pipe 90 connected with the first vacuum pump, and to insure effective exhaust from said pockets, there is formed in the inner surface of the casing of the discharge chamber a groove 91 extending around the same for a sufficient length to permit of exhausting the air from a pocket, while the valve is rotating through a considerable angular distance.

I claim:

1. In a continuous rotary double seaming machine, the combination with a continuously rotating carrier having a plurality of can body receiving pockets, of a plurality of axially rotatable can holder chucks mounted on said carrier, a plurality of sets of double seaming rollers mounted on said carrier, and direct pressure means for actuating said seaming rollers as the carrier rotates, an external annular gear for rotating said carrier, a central driving shaft extending axially through said rotary carrier, and connecting gearing for communicating motion from said central driving shaft to said annular external gear on the carrier, substantially as specified.

2. An apparatus of the character described, having a chamber, means for exhausting air from said chamber, a rotary can carrier in said chamber, means for rotating said carrier, means for introducing cans in succession into said chamber while main-

taining a vacuum therein, means for causing said cans to be engaged by said carrier to be transported thereby, and means for seaming said cans while being so carried, substantially as described.

3. In a vacuumizing and double seaming machine, the combination of a seaming chamber, a vacuumizing chamber, means for feeding a can to said vacuumizing chamber, 65 mechanism for feeding said can from said vacuumizing chamber to said seaming chamber, provided with means for preventing the passage of free air through said vacuumizing chamber to said seaming chamber, means 70 in the latter chamber for seaming the can, means for producing a vacuum in the vacuumizing chamber, and means for maintaining the vacuum in the seaming chamber, substantially as described.

4. In a vacuumizing and seaming machine, the combination of a vacuumizing chamber, means for feeding cans and tops thereinto, and for depositing the tops upon the cans, means for producing a vacuum 80 therein, a seaming chamber, means for maintaining a vacuum therein, mechanism for transporting a can with the top thereon from said vacuumizing to said seaming chamber, said mechanism being provided with means 85 for preventing the passage of free air through the vacuumizing chamber to the seaming chamber, and means in said latter chamber for seaming the tops upon the cans therein, substantially as described.

5. In a vacuumizing and seaming machine, the combination of a vacuumizing chamber, means for producing a vacuum 95 therein, means for feeding cans thereinto in succession, a seaming chamber, means for maintaining a vacuum therein, means for introducing tops into the seaming chamber, mechanism for transporting the cans in succession from the vacuumizing into the seaming chamber, said mechanism being provided 100 with means for preventing the passage of free air through said vacuumizing into the seaming chamber, and means in said seaming chamber for seaming the tops upon the cans, substantially as described.

In testimony whereof I have hereunto set my hand in the presence of two subscribing witnesses.

LUDWIG WURZBURG.
